(57) **CLAIM**

The ornamental design for an ear hook with adjustable boom mounted light, as shown and described.

DESCRIPTION

FIG. 1 is a perspective view of the ear hook with adjustable boom mounted light of the instant invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view illustrating the instant invention positioned around the ear of an individual;

The portions of figures illustrated in broken lines are for environmental purposes only and form no part of the claimed design.
